H. H. AHERN

HEEL AND ARCH SUPPORT

Filed April 5, 1928

INVENTOR:

HARRY H. AHERN,

BY Heising & Fairbanks
ATTORNEYS

UNITED STATES PATENT OFFICE.

HARRY H. AHERN, OF NEWPORT NEWS, VIRGINIA.

HEEL AND ARCH SUPPORT.

Application filed April 5, 1928. Serial No. 267,489.

My invention relates to a new and useful heel and arch spring support which is adapted to be detachably positioned within a shoe to provide resilient support for the heel and arch of the foot.

My invention further relates to a heel and arch support of this character which, while giving maximum resiliency and support, is light in weight and provides a soft tread.

10 My invention further relates to a heel and arch support formed of metals of different electro-static properties so that a galvanic current is produced by the acid incident to foot perspiration.

15 My invention further relates to a heel and arch support which is so shaped as to fit the bottom contour of the foot and which does not tend to slip or to be displaced within the shoe.

20 To the above ends my invention consists of an arch support composed of two upper and lower spaced flexible metal plates having a rear depressed portion for the reception of the heel and an upwardly curved portion 25 adapted to contact with the arch of the foot, and having a bottom spring to provide a resilient support.

My invention further consists of various other novel features of construction and advantage, all as will be hereinafter described and claimed.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the accompanying drawings:—

45 Figure 1, represents a perspective view of a heel and arch support, embodying my invention shown positioned within a shoe, the latter being shown in dotted lines.

Figure 2 represents a bottom plan view of 50 my novel heel and arch support shown detached.

Figure 3 represents a longitudinal section on line 3—3 of Figure 2.

Figure 4 represents a transverse section on 55 line 4—4 of Figure 2.

Referring to the drawings in which like

reference characters indicate like parts, 1 designates a novel heel and arch support embodying my invention, comprising an upper flexible metal plate 2 and a lower flexible metal plate 3. The lower flexible metal plate 3 is secured to the upper flexible plate 2 by the continuous lip or flange 4, bent downwardly and inwardly to enclose and engage the edge of the lower plate 3, it being understood that said plates may be secured to each other in any other desirable manner. A spring 5 is secured to the bottom plate 3 by means of the rivets 6 or the like, said spring being curved downwardly or bulged outwardly as at 7 and again upwardly as at 8, and terminating in the downwardly bent free end portion 9. The upwardly curved or humped portion 8 bears against a shield 10 which is a plate interposed between said curved or humped portion of said spring and the juxtaposed portion of the bottom plate 3, said shield being secured to the plate 3 in any suitable manner and preventing said plate from abrasion. The plates 2 and 3 80 are spaced apart as at 12 to provide resiliency and softness of tread. The plates 2 and 3 are further provided with the aligning rear depressions 14 for the reception of the heel of the foot which as is well known from human anatomy protrudes lower than the arch and instep of the foot. The metal plates 2 and 3 are also provided with the convexed portion 17 forming a rest or support for the arch of the foot, said convexed portion terminating in a substantially flat or horizontal portion 15 which is slightly bent downwardly at its front extremity as at 16, to prevent the foot or the stockings from catching with the front end of the arch support when the foot is withdrawn, that is, when the shoes are taken off. The space between the upper and lower plates 2 and 3 is at its maximum at about the central portion of said plates, that is, at the point aligning with the arch of the foot, and gradually tapers or decreases as the heel and instep portions are approached, where little or no resiliency or support is needed. Similarly, the spring 5 is of greatest curvature and tension at the point corresponding to and aligning with the arch of the foot, thus giving maximum resilient support to the arch of the foot, as will be apparent from Figure 3.

By providing the space 12 between the plates 2 and 3, I provide a resiliency and softness of tread which would not be available if

a single plate of sheet metal were employed. This resiliency is further enhanced by the provision of the spring 5 which while not occupying additional space, is so positioned as 5 to enhance the resiliency of the convexed portion 17 which supports the arch of the foot. The shield 10 is interposed between the end of the spring 8 and the juxtaposed point or portion of the lower plate 3 to prevent wear- 10 ing out of the latter by the friction of the curved spring portion 8 as the pressure on the spring varies during the act of walking. Thus as the weight of the body is transferred from the heel of the foot to the instep, and as 15 the heel is raised with respect to the fulcrum point just behind the toes, the entire weight of the body rests momentarily upon the arch of the foot. As the weight of the body progresses forward, from the rear to front por- 20 tion of the arch of the foot, the spring 5 and the plates 2 and 3 are correspondingly and proportionally compressed, thus providing a "sliding" or shifting support corresponding with the shifting of the weight of the body, 25 and thus keeping the arch of the foot constantly supported and reinforced.

By providing the depression 14 I not only provide a seat for the heel of the foot, but I am also enabled to use my novel arch and heel 30 support without the aid of any auxiliary fastening devices, that is, I provide a device that will retain its proper position and which will not slide or shift within the shoe.

If desired, I may employ upper plates 2 of 35 metals having different electro-static properties such as zinc, and copper, thus forming an anode and a cathode or positive and negative poles which when acted upon by the acid incident to perspiration of the feet, will gen- 40 erate a galvanic current which possesses admitted therapeutic advantages.

My novel heel and arch support is detachable and may be made in various standard sizes to fit various sizes of shoes and that the 45 same may be adapted for use in men's, women's and children's shoes indiscriminately.

It will further be apparent that I have devised a heel and arch support which is extremely light compared to conventional arch 50 supports heretofore known and employed, and that my novel heel and arch support tends to cool the feet since the metals from which it is made are good heat conductors which conduct and radiate heat at a much quicker rate 55 than leather and other materials heretofore employed, which as is well known are heat insulators or poor conductors.

I am aware that the invention may be embodied in other specific forms without depart-

ing from the spirit or essential attributes 60 thereof, and I therefore desire the present embodiment to be considered in all respects as illustrative and not restrictive, reference being had to the appended claims rather than to the foregoing description to indicate the 65 scope of the invention.

Having thus described my invention what I claim as new and desire to secure by Letters Patent, is:

1. In a device of the character stated, an 70 upper plate and a lower plate having a contour to fit the rear portion of a shoe, said plates being secured together at their outer peripheral edges but spaced apart with respect to each other at their intermediate and 75 rear portions, and a bottom spring secured to and extending rearwardly from the front portion of said bottom plate and having its free end adapted to bear upwardly thereagainst, there being aligning depressions for 80 a heel in said upper and lower plates extending rearwardly from the free end of said spring.

2. In a device of the character stated, an 85 upper plate and a lower plate formed of spring metal and having rear depressed heel and front convexed arch portions, said plates being assembled in spaced relation to each other, a bottom spring having one end thereof secured to the front portion of said bottom 90 plate and having its rear free end juxtaposed to said bottom plate adjacent the junction of said heel portion and said arch portion, and a protecting shield intermediate the free end of said spring and said bottom plate to prevent abrasion of the latter.

3. In a device of the character stated, an 100 upper plate and a lower plate having a contour to fit the rear portion of a shoe, said plates being assembled in spaced relation with respect to each other by a peripheral flange on said upper plate, a bottom spring secured to the front portion of said bottom plate and extending rearwardly therefrom and having its free end adapted to bear up- 105 wardly thereagainst, and a protecting shield intermediate said bottom plate and the free end of said spring to prevent abrasion of said plate, there being aligning depressions for a heel in said upper and lower plate positioned rearwardly from the free end of said spring, the maximum space between said plates being juxtaposed to the free end of said spring and the front portions of said plates being in contact from a point beyond the fixed end 110 of said spring.

HARRY H. AHERN.
